(57) **CLAIM**

The ornamental design for an elongate base member for a lace tightening device as shown and described.

DESCRIPTION

1. Elongate base member for a lace tightening device

1.1 : Perspective

1.2 : Back

1.3 : Top

1.4 : Left

1.5 : Right

1.6 : Front

1.7 : Back

The elongate base member is positionable on an article, such as an article of footwear; A lace tightening device can be attached to the elongate base member to couple the lace tightening device with the article; The portions illustrated by solid lines are the portions for which the claimed design is intended; The broken lines in the drawings represent environment that form no part of the claim.

1 Claim, 7 Drawing Sheets
